CONTROL MECHANISM FOR BOWLING PIN SPOTTING MACHINES

Roger E. Dumas, Snyder, N. Y., assignor to American Machine and Foundry Company, a corporation of New Jersey

Application April 6, 1949, Serial No. 85,893

14 Claims. (Cl. 273—43)

1

This invention relates to bowling pin spotting machines, and more particularly to improvements in automatic bowling pin spotting machines for use with bowling alleys provided with a pit at the rear end thereof into which bowling pins fall or are delivered and are conveyed therefrom by bowling pin handling mechanism which delivers the pins, one after another, to a pin assembling mechanism or distributor where the pins are arranged in a predetermined order or pattern for delivery to suitable spotting mechanism for placement on the pin supporting deck of a bowling alley.

The present invention contemplates the provision of improved and novel control mechanism by providing control devices engageable by pins moving from the conveying mechanism which delivers the pins from the pit of a bowling alley to the assembling device of the distributor. For example, the distributor may include a set of ten pin receiving cups which are movable one after another into and out of pin receiving position at a pin receiving station wherein pins delivered one by one from a transporting conveyor are dropped into the cups seriatim until a predetermined number of cups, usually ten, are full and the distributor mechanism is ready to effect the delivery of pins held in the cups into spotting devices on a pin spotting table which is moved to and from the pin supporting deck of the alley and a receiving position beneath the distributor mechanism for the proper placement of the pins in spotting arrangement on the playing deck of the alley.

Mechanism comprising the present invention is adapted primarily for use with a machine such as is shown in co-pending application Serial Number 34,695, filed June 23, 1948, by Henry W. Phillips, and the machine illustrated in co-pending application Serial Number 59,706, filed November 12, 1948, by John M. Fluke and Thomas Flint. While mention of the above referred to co-pending applications is made as disclosing machines in which the present invention can be used, it is to be understood that the structure disclosed herein can also be adapted for use in other bowling pin spotting machines employing conveying mechanism for removing pins from the pit of a bowling alley and delivering them to pin assembling and distributing mechanisms.

It is an object of this invention to provide a novel bowling pin handling mechanism including conveying mechanism for removing pins from the pit of a bowling alley, and aligning and transferring devices having associated therewith con-

2

trol means which provide for the proper delivery of bowling pins one by one into assembling devices in the distributor for subsequent delivery to a pinspotter for placement on the pin supporting deck of the alley.

It is a further object of the invention to provide an improved pin assembling and distributing mechanism provided with control devices for operating such mechanism wherein a succession of pins is moved one by one free from lateral movement into cups of a distributor mechanism which are moved one after another into position to receive pins, including a control device which insures that an empty cup is positioned to receive each pin prior to the arrival of a pin for delivery into an empty cup in the distributor.

The invention also consists in the provision of a novel bowling pin handling mechanism having spaced pin actuated, electrical trip members which control the delivery of pins to a distributor provided with a plurality of spaced cups and means for moving an empty cup into position to receive a pin prior to the arrival of a pin at the point of delivery into each empty cup.

It is a further object of the invention to provide a more flexible and rapid system for handling bowling pins and effecting their delivery into a distributor mechanism ready for delivery into a pin spotter, and a plurality of control devices operated by each pin conveyed into an empty cup of said distributor for controlling the conveying means which move pins from the pit of a bowling alley for delivery into the cups of the distributor and for controlling the timed operation of said distributor.

An added object of the invention is to provide a novel pin handling system and distributor for a bowling pin spotting machine which reduces materially the amount of time lost in handling the pins for spotting and which therefore increases materially the number of sets of pins spotted on a bowling alley per hour, with less wear and tear on the machine.

The invention also includes novel control devices for the pin handling and distributing mechanism of a bowling pin spotting machine, and a safety device which insures adequate time for the discharge of all bowling pins from the distributor mechanism into the pin spotting devices of the pin spotting table of the machine.

The invention also consists in the provision of control mechanism which increases the flexibility between the pin collecting and distributing functions of a pin spotting machine, and spotting and respotting mechanisms associated therewith by

permitting a variable time of unloading of the distributor with respect to the spotting and re-spotting table depending upon the requirements of the game and the results obtained by a bowler by each ball rolled, which thereby determines the nature of a table cycle in spotting and re-spotting pins on the alley and the need of the table for a new set of pins for spotting.

With these and other objects not specifically mentioned in view, the invention consists in certain combinations which will be hereinafter fully described, and set forth in the claims hereunto appended.

In the accompanying drawings, which form a part of this specification, and in which like characters of reference indicate the same or like parts:

Fig. 1 is a fragmentary side elevation of a portion of an automatic bowling pin spotting machine, illustrating an embodiment of the present invention.

Fig. 2 is a fragmentary rear elevation of the pin elevating mechanism of the machine on an enlarged scale, viewed from the left of Fig. 1.

Fig. 3 is a top plan view of the machine, partly in section, illustrating the pin distributor, a portion of the pin elevating mechanism, and that part of the novel control means which is associated with the mechanism for transporting pins from the elevating mechanism to the distributor.

Fig. 4 is a plan view, on an enlarged scale, showing a cycling cam and associated electrical switches which control, in part, the step by step movements of the distributor.

Fig. 5 is a side elevation of the same shown partly in section.

Fig. 6 is a fragmentary, sectional plan view of the pin distributor, taken approximately on line 6—6 of Fig. 1.

Fig. 6a is a fragmentary side elevation illustrating mechanism used in driving the distributor step by step.

Fig. 7 is a detail elevation of a solenoid-operated stop for the distributor platform or spider, on line 7—7 of Fig. 6.

Fig. 8 is a side elevation, on line 8—8 of Fig. 6, illustrating a switch and associated parts for controlling operation of the distributor platform or spider.

Fig. 9 is a wiring diagram illustrating a suitable electrical circuit and connections thereof to the control mechanism and operating devices of the invention.

Figure 10 is an isometric view of suitable latching mechanism for the distributor, and

Figure 11 is a rear view showing mechanism for returning and holding the trap door of cup C5 in pin supporting position.

In a machine, such as that shown in the Fluke and Flint, and Phillips applications referred to above, it is to be noted that there are two parts of the machines disclosed therein which have a direct bearing on the number of games per hour such machine will produce, that is, the number of sets of pins that the machine will place upon the playing deck of a bowling alley per hour.

These are:

(1) The ability of the machine to respot pins and to process pins through the back end, elevator, transfer belts, distributor and table for spotting.

(2) The ball handling speed of the machine and the length of time it takes the ball to return to the bowler together with the time required

for the bowler to pick up the ball and deliver it to the machine for the next ball.

This invention involves creating additional flexibility between the movements of the table as dictated by the time at which balls are received by the machine and the handling of pins by the remainder of the machine for delivery to the table for spotting.

In a machine such as disclosed in the Fluke and Flint application a set of pins from a preceding frame is conveyed, aligned and delivered into the cups of the distributor ready for loading into the spotting table by the time the first ball of the next frame is rolled and the table is lowered to test for the presence or absence of pins standing on the pin supporting deck of the alley. In the operation of said machine, it is a requirement for this cycle that a new set of pins be delivered to the table at the beginning of each frame. The time available for effecting the delivery of pins under customary bowling conditions is equivalent to the time from the last pin being swept into the pit from the preceding second ball cycle until the receipt of the first ball of the next frame to be rolled or the next first ball cycle of the machine's operation.

For example, this time may be say approximately eight seconds plus the bowler's time of twelve seconds, or twenty seconds total. The pin handling ability of the machine disclosed in said Fluke and Flint application for example, may be one set of pins per twenty-six seconds total time, including the time required for conveying the first pin to be delivered into the distributor from the pit of the alley. When pins are discharged from the distributor to the pin receiving table at the beginning of the first ball cycle, i. e. after the first ball of the frame is thrown, as in the machine of the type shown in the Fluke and Flint application, above referred to, these pins are held in the table for a minimum of say eight seconds in the case of a strike, or a maximum of approximately thirty seconds in the case of a normal cycle involving the throwing of two balls to complete the frame. This storage time represents dead time insofar as the pin handling process is concerned.

In the present invention this dead time is substantially eliminated by having the pins delivered from the loaded distributor into the table at the end of the first ball cycle, thereby allowing, for example, an additional fifteen seconds for the conveying, aligning and delivery of pins into the distributor before any delay is caused in the table operating cycle. The overall time of handling pins from the time they are placed on the pin supporting deck of the alley until the same group of pins is again delivered to the spotting device of the pin spotting table is reduced to approximately thirty seconds, as compared to approximately forty-five seconds, as a result of this invention.

According to the invention, the pin spotting table is never required to support more than ten pins at any one time, thereby reducing the counterweighting or power necessary to operate the table.

The novel control mechanism of the present invention also allows the loading of pins for a strike cycle in the middle of a strike cycle, i. e. where the pin spotting table has made more than one trip down to determine the fact that a strike has been made and has returned to its upper or pin receiving position, where pins are discharged thereto from the distributor, and then returns to pin spotting position adjacent the pin supporting

deck to spot the pins received from the distributor.

Thus according to the invention, during a strike cycle, pins are required to be supported in the table only during the length of time for the table to move from its pin receiving to its spotting position or a total of approximately four seconds. In earlier machines, such as in the above referred to Fluke and Flint application, pins are supported in the table before the latter moves downwardly to test for the presence or absence of standing pins on the alley after the throwing of a ball, or after a strike is made, and are carried upwardly in the table, and not spotted on the alley until the table makes its second trip down which requires a total of approximately eleven to twelve seconds.

The culminating effect of these reductions in time is to permit a slower elevator speed and a slower transfer belt and distributor speed for a given number of table cycles per hour since the elevator system now operates at a more uniform pace rather than having to operate fast at short intervals of time and then wait until the pins are supplied by the action of the bowling game.

In general, the pin spotting machine illustrated for disclosing an embodiment of the present invention, includes an alley X, the rear end or playing zone of which is seen in Fig. 1, and at the rear of which the pit 20, for the reception of pins P, and thrown balls, is located.

Extending from the rear of the structure forwardly along the pit 20 and the alley X are the usual side walls or kickbacks 22. Disposed between and connected to the rear ends of the kickbacks 22 is a vertical skeleton framework 24, Fig. 2, including opposite spaced side uprights 26 connected at bottom and top by horizontal members 28 and 30 respectively and by intermediate members 32.

Suitable means, such as an endless, substantially horizontal belt or apron 40, Fig. 1, may be provided for carrying the pins and balls in the pit 20 rearwardly to the pin and ball elevating means. This belt 40 may be driven by any suitable means in the direction of the arrow, Fig. 1, as by shaft 42, Fig. 2, operatively connected, by means not shown to a sprocket chain 44 engaging a sprocket on an end of the rear roller 46 of the apron 40, Fig. 1.

Pins P, so delivered, enter lengthwise a trough or space 53 between horizontal transverse guides 56, Fig. 2, between which travel, in the direction of the arrows, Fig. 2, the lower runs of a pair of endless conveyor chains 52 of the pin elevating conveyor 49. These chains pass upwardly (at the left, Fig. 2) to the top of the frame 24, across the top thereof below frame cross member 30 and thence downwardly at the right hand end of frame 24, Fig. 2, and thence to the guides 56. These chains carry between them equally spaced pin carriers or flights 56, which engage pins P, disposed in trough 53 between the guides 56 and elevate them (at the left, Fig. 2) through an elongated enclosed chute 51 to the top of frame 24 for discharge, one after another, upon an inclined chute 60. The pins P fall from this chute 60 upon a longitudinal forwardly inclined plate 62, Figs. 1 and 2, which guides them to the pin transport mechanism K, to be described, which delivers them to the distributor D. The mechanism just described is substantially the same in construction and operation as that disclosed in the above referred to Phillips application, and since it forms no specific part of the

present invention, further detailed description and illustration are deemed unnecessary.

The pin elevating chains 52 may be driven in any suitable way, as by a motor M3, suitably braked, Figs. 1 and 2, connected by a belt and pulleys of suitable size, to a shaft 64. A sprocket (not shown) on shaft 64, together with suitable intervening sprockets and chains, connects shaft 64 to a shaft 66 on which are mounted three sprockets 68 (see Figs. 1 and 2), two of which mesh with the chains 52 and serve to drive those chains at a speed such that pins being engaged and elevated by the flights 56 will arrive in timed relation and be delivered as needed, to the pin transport means, designated generally K.

Motor M3, above mentioned, could run continuously, but in accordance with the novel control mechanism of this invention, it is stopped at intervals in accordance with the delivery of a suitable or required number of pins, for example ten, into the distributor D, to fill the distributor and to then prevent the arrival of additional pins beyond the number required. After distributor D has been unloaded of its charge of pins, motor M3 is started again and conveyor 49 elevates pins removed from pit 20 for delivery to the distributor.

Distributor D, above referred to, is best seen in Figs. 3 and 6, and is arranged above a suitable spotting and respotting table T, Fig. 1, which will be referred to later. Bowling pins to be distributed are delivered one by one in succession from the elevating mechanism of Fig. 2 by way of the pin transport mechanism K referred to, so that they are free to fall one after another into the cups or pockets in distributor D at the pin delivery station.

As shown in Figs. 1 and 3, distributor D is disposed between spaced upright side frames 101 and is supported on a cross channel 100 extending transversely above the distributor and connected at its ends to the top members of the side frame 101. Distributor D is provided with ten pin receiving cups C, designated C1-C10 inclusive, corresponding in number to the number of pins customarily constituting a set or frame. Cups C1-C10 are preferably of hopper or funnel formation having circular open lower ends, see Fig. 6.

In the illustrated embodiment, the ten cups C1-C10, are mounted on a horizontal supporting frame 102 secured to a vertical shaft Y mounted in suitable bearings in a gear box 103 mounted on the web of the cross channel 100. Beneath the distributor frame 102, the shaft Y rotatably supports the hub 113 of a pin supporting platform of spider 114 provided with a plurality of radial arms having pin supports 115 which normally extend beneath and adjacent to the open lower ends of the cups C for supporting pins P in the cups. Relative motion between the cups and the spider is provided so that when desired, the spider may be shifted relatively to the shaft Y and the cups to clear the open ends of the latter and allow simultaneous discharge of the ten pins in cups C1-C10 inclusive to the table T. In the disclosed arrangement, the discharged pins fall from the distributor D into funnels F of the table, see Fig. 1.

The pin transport mechanism is illustrated in Figs. 1 and 3. Pins conveyed to distributor D by transport mechanism K, drop into whichever cups C1-C10 of distributor D come into line therewith sequentially at the pin receiving station at the discharging end of transport mecha-

nism K. Owing to the position of pin No. 5 in the standard triangular arrangement on the alley for play, cup C5 is disposed between and close to cups C8 and C9 and is inclined and of such form as to guide a pin received therein to the appropriate spotter pin funnel or guide F of table T. The other cups C10, C6, C3, C1, C2, C4 and C7, are spaced apart twice the angular distance existing between cups C8, C5, and C9, as indicated in Figs. 1 and 3.

Shaft Y is driven intermittently to move the empty cups to the receiving station, and filled cups away therefrom, as stated. The drive for shaft Y may be obtained from a suitable motor M2 and gear reduction unit 120 mounted on the frame of the machine. Shaft 122 of unit 120 has a pulley and belt connection, as by belt 123, to a pulley 124 operating the driving section of a one-revolution clutch 126 of any known or standard type, such as a #2 Hilliard clutch. The driven element 125 of the clutch 126 is secured to shaft 128 supported in bearings in the gear box 103, mounted on channel 160.

The driving connections between the shaft Y and the one-revolution clutch 126 are illustrated in Figs. 3 and 5.

As shown in Figs. 3 and 5, shaft Y has secured thereto a gear 128a which meshes with a pinion 129 secured to a shaft 129a mounted in bearings in the gear box 103.

Also mounted on shaft 129a is a bevel gear 130a meshing with a bevel pinion 131 secured to the inner end of the driving section 131a of the clutch 126. The ratio of the bevel gears 130a and 131 effects a 3:1 reduction; and the ratio of spur gears 128a and 129 effects an additional reduction of 6:1. The overall result is a drive ratio of 18:1 between clutch 126 and shaft Y.

Clutch 126 is operable by an intermittently actuated solenoid S2, Fig. 6a, connected to a spring engaged latch lever 130. Lever 130, as shown in Fig. 6a normally latches a cam 134 of the clutch 126 to hold the clutch disconnected. When the solenoid S2 is momentarily energized, latch lever 130 is moved to free the cam 134, whereupon the clutch is thrown in, and is now able to make one revolution to operate the above described gearing in box 103 to rotate shaft Y and the distributor D and spider 114, at the desired speed, in a counterclockwise direction, Figs. 3 and 6. Thus one index of distributor D is made.

Associated with the cam 134 of clutch 126 may be arranged a suitable stop member 130b which co-operates with a stop on the driven clutch element to prevent overrunning, in a manner well known in clutches of this sort.

As described in detail later, the indexing of distributor D through movement of its frame 102, is such that successive empty cups C1-C10 are presented at the pin receiving station at the end of the pin transport device K in proper timed relation. Assuming the parts to be in the position of Fig. 3, with the first pin of a new set received in cup C5, the operation of clutch 126 is as follows: Movement of cup C9 to the present position of cup C5, one revolution. Indexing of cups C10, C6, C3, C1, C2, C4, C1 and C8 requires two revolutions of clutch 126 to present each of those cups for delivery of a pin P thereto. In moving cup C5 into pin receiving position, one revolution of the clutch is called for.

Solenoid S2 is actuated, in accordance with the invention, by a switch and other electrical elements associated with the pin transport device K, as will be explained. The step by step rota-

tion of the distributor shaft Y for indexing distributor D, through operation of solenoid S2, as explained, is further controlled by a cycling cam 140, Figs. 3-5, and related switches DA, DB and DC arranged in the control circuit. Cam 140 is fixed to shaft Y above gear box 103.

The pin transport mechanism K and the electrical control devices associated therewith, in accordance with this invention, are constructed as follows, see Figs. 1, 2 and 3. In those views are seen a pair of spaced, endless V-belts 150, disposed as in the Phillips application Serial Number 34,695 and the Fluke and Flint application Serial Number 59,706, earlier referred to.

Belts 150 are mounted at the front on a pair of idler pulleys 152 journailed adjacent the distributor D in bearings on the machine frame. The rear ends of the belts pass over drive pulleys 154 on a drive shaft 156 mounted in bearings in the rear frame 24, Fig. 3. The upper runs of the belts 150 incline as shown in Fig. 1, and travel in the direction of the arrow, being spaced to support and carry pins forwardly to the pin receiving station adjacent distributor D. The lower runs of the belts engage adjustable idler pulleys 158, Fig. 1, supported on the frame 24 for providing the desired belt tension.

Drive shaft 156 is driven from motor M3 in a manner to stop the movement of the belts 150 when motor M3 is stopped for stopping the pin elevating chains, as described. For this purpose, see Fig. 2, shaft 64 has a sprocket thereon (not shown) for driving a chain 160, operatively connected to a gear reduction unit 162, to which one end of shaft 156 is secured. At its other end, beyond the pulleys 154, shaft 156 has suitable gear connections to shaft 42 from which sprocket 44 and associated elements are driven for actuating the pit apron 40, as described.

Belts 150 are spaced apart a distance somewhat less than the maximum diameter of a pin so that they may engage and support the body of a pin at approximately its maximum diameter and move it along the transport device from the back end of the machine to a point of discharge adjacent a distributor cup. As each pin P travels forwardly on the belts 150, its head usually depends below the belts.

To ensure that each pin will be delivered butt end forward for proper delivery, butt down, into the cups C, there is provided, between and somewhat below the upper runs of the belts 150, an inclined guide plate 170 terminating at its front end in a curved pin directing section 172, over which pins slide downwardly into the cups, see Fig. 3.

The rear end of guide plate 170 is also downwardly curved at 174. Pins leaving the inclined plate 170 of the pin elevating mechanism with their butt ends foremost, will engage and rest directly on the belts 150 and be transported at once thereby. However, some pins will be directed head end down by the plate 170, in which case the heads thereof will drop between the belts 150 in rear of the curved end 174 of plate 170. The bodies of such pins will also ride on the belts, dragging the pendant heads against the end 174. Thus, those pins will be oriented to proceed butt end foremost since the heads of those pins will be restrained against riding up onto plate 170 until after the butts thereof have gone forward.

In accordance with the novel control mechanism of this invention, there are operatively associated with the transport mechanism K de-

scribed, three trip switches A, B, and C. Switch A, normally closed, is secured to a side member of the transport frame 180, see Fig. 3, and has a pivoted actuator *a* extending over the adjacent upper run of one of the belts 150 so as to be in the path of pins moving on the transport K. Switch B, normally open, is similarly mounted at the opposite side of frame 180, and has a pivoted actuator *b* arranged to be likewise engaged by pins P which have passed switch A. Finally, 10 switch C, disposed near the front or discharge end of transport device K, is also normally open and is operable by pins P engaging its pivoted actuator *c*, if and when they have passed switch B and the belts 150 are running.

To assist in an understanding of this invention and the operation of the machine, as controlled thereby, it might be stated here that a desirable speed ratio of the main sections of the machine is provided by the drive means described, such that the chains 52 of the rear end pin elevating mechanism if running without intermission and each flight 56 picks up and elevates a pin, are then capable of handling approximately 30 pins per minute.

Under similar conditions the belts 150 of the transport mechanism, driven by the means described, may transport approximately 50 pins per minute.

While the distributor D with all cups C full, can only carry 10 pins at any one time, it nevertheless, due to the speed at which it is driven, can receive and handle pins at an overall rate of 60 pins per minute. Thus the three sections, each in the order described, may carry pins in excess of those carried by the preceding section, thereby ensuring freedom of operation without jamming due to creeping up of pins from one section to the next.

As shown clearly in Fig. 6, spider 114 is yieldingly held by a spring 185, one end of which is secured at 186 to a post depending from the distributor frame 102. The other end of the spring 185 is attached to a stud 187 on spider 114. As will be seen upon reference to Figs. 3 and 6, a counterclockwise motion of distributor frame 102 and its cups relative to spider 114 will move the open ends of the cups away from the pin supporting members 115 of the spider so that pins are no longer supported by those members, and drop into spotter funnels F.

It should here be recalled that cup C5 is of different construction than that of the other cups of the distributor for the purpose of enabling it to discharge a pin into the No. 5 position of the triangular arrangement required for spotting. For this purpose, the lower end of cup C5, instead of being closed by a pin support 115, has mounted therein a door 190 which, when the distributor is full and pins are to be discharged, is released by suitable latch mechanism to enable pin No. 5 to be discharged from cup C5 simultaneously with the discharge of all the other pins from the cups C1-C4 and cups C6-C10.

The construction and automatic operation of door 190 on cup C5 is substantially the same as that illustrated and described in the Fluke and Flint application Serial Number 59,706, previously referred to.

As shown in Figs. 10 and 11, trap door 190 is pivotally attached at 330 to the lower edge of the front inclined wall of cup C5, and is normally held in closed or pin supporting position by a cam 354 engaged by cam follower 332 supported on arm 331 on trap door 190. Spider 114 is provided

with a frame portion 352 extending outwardly therefrom beneath the lower portion of cup C5. When distributor frame 102 moves in a counterclockwise direction relative to spider 114, as described hereinbelow, cam follower 332 will move out of engagement with cam 354 and trap door 190 then drops downwardly, thereby permitting the discharge of a pin from cup C5 to its spotter guide F.

Cam 354 is fixed to the top of frame portion 352 in position to be engaged by cam follower 332 when spider 114 and distributor frame 102 are secured by a suitable latch mechanism against motion relative one to the other. This latch mechanism includes a plate 367 attached to and depending from the outer side of cup C5, and provided with a notch 367a. A latch 368 pivotally mounted on cam 354 engages notch 367a, and acts to prevent relative separating motion between distributor frame 102 and spider 114 until it is desired to effect the delivery of pins from cups C1 to C10 into spotter guides F. The free end of latch 368 is provided with a cam follower 368a.

At such times as distributor D and spider 114 25 are required to move in unison, latch 368 is retained releasably in notch 367a of plate 367 by a spring (not shown). Thus latch 368 is in engagement with notch 367a during the first nine indexing movements of the distributor and spider.

30 Near the completion of the ninth movement, latch roller 368a runs on a cam 369 mounted on an extension 369a of the machine frame, and disposed in the path of latch roller 368a. In this way, latch 368 is swung about its pivot against the 35 action of the above mentioned spring and is disengaged from notch 367a. It will be seen therefore that as the result of the unlatching operation described, on the next movement of frame 102, cam follower 332 will move off cam 354, whereupon the trap door 190 will move downwardly 40 and discharge the pin supported thereby, as described above.

During the step by step motion of frame 102 of distributor D in loading pins into the cups thereof, spider 114 is releasably held in its pin supporting position and moves therewith. During this step by step motion of the frame 102 and spider 114 in a counterclockwise direction, a finger 192 projecting from one of the pin supports 115, see Figs. 6 and 7, engages a stop 194 carried by a lever 196 pivotally mounted upon the side frame 101. Between its ends, lever 196 has pivoted thereto the armature of a solenoid S3 also mounted on the frame 101 and which is energized after the relative separating motion between spider and distributor is completed and a set of pins has been delivered into spotter funnels F.

Upon actuation of solenoid S3, lever 196 will be raised, causing the stop 194 to release finger 192 on spider 114, whereupon, due to the action of the spring 185, spider 114 will be moved on shaft Y to relocate the pin supports thereon in pin supporting relationship beneath distributor cups C1-C10.

65 In Fig. 6, the position of the parts is such that pins have been discharged from the distributor cups C1-C10, frame 102 has moved one step beyond the pin discharge position and the spider 114 has been released from the stop 194 and has caught up with the distributor cups, so that the pin supports 115 thereof are again in pin supporting position beneath the cups and door 190 has been returned and latched in closed position. A suitable stop is provided to arrest the spider when 70 it has been moved relatively to the distributor by 75

11

spring 405. If desired, such a stop may comprise the latch 368 which engages in notch 367a in latch plate 367 mounted on cup C5, as clearly shown in the above Fluke and Flint application.

The foregoing latch means enables distributor frame 102 and spider 114 to be releasably locked together during the step by step motion of both elements while pins are being delivered one after another into cups C1-C10.

The foregoing arrangement is effected during the first nine indexing or step by step motions of the distributor and spider. Near the completion of the ninth movement, latch 368 is moved out of notch 367a, and as the tenth step movement of the distributor occurs and all cups are filled, finger 192 of the spider moves into engagement with the stop 194.

As already mentioned, and as shown in Figs. 3, 4 and 5, a cycling cam 140, disposed in a horizontal plane, is rigidly secured to the upper end of shaft Y above the gear box 103. Operatively associated with cam 140 are switches DA, DB and DC, which (Fig. 5) are supported on brackets 200 projecting upwardly from the top of the gear box 103. The brackets are constructed to position the switches so that selected parts of the cam 140 can actuate desired switches during the rotation of the distributor D and cam plate 140 with the shaft Y.

Extending radially outward from the cam plate 140, is a series of eight cam lobes 202-216. Switch DA is disposed so that the roller 217 on its actuator 218 may be engaged successively by the lobes 202-216.

Switches DB and DC are positioned above the cycling cam 140 and are aligned respectively with cams 220 and 222 projecting upwardly from cam 140, as seen in Figs. 4 and 5. Cams 220 and 222 are located at different radial distances from the center of shaft Y, so that switch DB is engaged only by cam 220, and switch DC can only be engaged by cam 222 during rotation of cycling cam 140. When distributor frame 102 has arrived in a position in which cup C8 is at the pin receiving station in alignment with the transport belt 150, cam 220 has engaged and actuated switch DB.

As shown in Fig. 8, there extends upwardly from one of the arms of the spider 114 a post 230, see also Fig. 6, to the upper end of which is secured a cam plate 232. Secured to the underside of the frame 102 of the distributor D is a normally open switch 234 which, during certain relative motions between spider and distributor, is engaged and closed by the cam plate 232. The purpose of this switch will be described hereinafter.

At this time brief reference only has been made with respect to the table T sufficient to disclose the relation of funnels F thereof to distributor D. However, in order to enable the table to spot or respot pins on the alley, a vertical substantially straight line motion is imparted to it, the table for this purpose being movable on vertical guides 240 on the machine frame.

In order to effect the desired movement of table T, a horizontal shaft 241 extends across the top of the machine frame and is supported in bearings on the side members 101 thereof, see Fig. 3. This shaft has provided at each end thereof a crank 242. The free end of each crank 242 is connected by a link 243 to the free end of another crank 244. Each of the lower cranks 244 is secured to a pivot 245 on the adjacent side of the table. Thus, by rotation of the cranks 242, the table can be raised and lowered. The

12

means for driving shaft 241, see Fig. 3, may comprise a motor 246 which, together with a reduction gearing 247, is supported on the machine frame. Gear box 247 has a shaft 248 which, by suitable sprockets and chains, is operatively connected to the shaft 241 for rotating it as needed.

The table T, as disclosed in the Fluke and Flint application referred to, is provided with suitable pin respotting devices or grippers for picking up and respotting pins, if any, which remain standing after a first ball. Such respotting devices or grippers are diagrammatically suggested at T¹ in Fig. 1.

The operation and control of the table movements and the devices thereon may be effected through suitable electric circuits and appropriate devices, and since such are fully shown and described in the Fluke and Flint application, Ser. No. 59,706, it is deemed unnecessary to discuss such procedure in detail here.

Control circuit and operation

When the cup supporting frame 102 of the distributor D is in the position shown in Figs. 3 and 6, and the spider 114 is in its operative pin supporting position relative thereto, the following conditions will exist: Latching relay LR4, see diagram Fig. 9, will be latched. Latching relay LR6 will be unlatched. Contacts 259 of switch DC will be held in open position by cam projection 222 and the spider switch 234 will be closed due to the engagement thereof by cam 232 on the spider post 230, thereby energizing relay TR2 which may be a relay of the telephone type.

Operation of the bowling pin spotting machine illustrated in the drawings, and control of which is by the novel means of this invention, may be understood by reference to the electric circuit shown in Fig. 9 and the following explanation.

Switch A at the leading end of transport device K controls the delivery of pins to the pin transport means K from the elevating means at the rear of the machine by starting and stopping the pin elevating motor M3 in accordance with the delivery of a required number of pins by transport device K to distributor D.

Switch B, associated with the transport device K, controls the step by step indexing operation of frame 102 of distributor D as a result of pins passing by that switch except when the first pin of each set passes that switch, in which case no indexing of frame 102 is effected. The first pin of a new set passing over the transport device is received in the cup C5 of the distributor, thereby causing a "delayed index," as set forth in detail hereafter.

Switch C, adjacent the discharge end of the transport mechanism K, when operated by the first pin of a new set, as above mentioned, sets up the control circuit so that each following pin Nos. 9, 10, 6, 3, 1, 2, 4, 7 and 8, will index distributor frame 102 to locate a succeeding empty cup in pin receiving position.

In the operation of the machine, motor M3 will be started initially when all pins are in the pit or on the alley by the action of normally closed contacts 278 of switch A which energizes the coil of relay LR3. Relay LR3 contacts 280 then close and start motor M3. Subsequent starting and stopping of motor M3 is controlled by switch A and by a second circuit consisting of normally closed contacts 256 of cam switch DB, normally open contacts 258 of cam switch DC which are closed by engagement therewith of cam projection 222 and contacts 262 of relay TR2 now

closed due to the fact that switch 234 is operated, as a result of a previous delivery of a set of ten pins from the distributor to table T, thereby energizing the coil of and operating relay TR2. This second circuit will also energize the coil of relay LR3 thereby closing contacts 289 and starting motor M3.

Motor M3 now operating, will drive the pin elevating chains 52 and also the belts 150 of transport device K for delivery of pins one by one to cups C1-C10 of distributor D.

The first pin that engages actuator a of switch A in the LR3 circuit opens switch A but the motor M3 is not stopped since relay LR3 is energized by a separate circuit described previously.

The first pin passing beyond actuator a of switch A to switch B actuates the latter and closes contacts 282 without effecting any indexing movement of frame 102. This is because the circuit to the power relay PR2, which operates the one-revolution clutch solenoid S2, controlling the movement of frame 102 of distributor D is open since the contacts 250 on latching relay LR6 are open, the relay being unlatched at this time.

The first pin, travelling by movement of transport mechanism K is now being discussed. It will, after passing switch B, engage actuator c of switch C closing contacts 286 and making a circuit through the latching coil of the latching relay LR6, thereby causing that relay to be latched. This relay LR6 is mechanically held in latched position. Continued travel of the first pin causes it to pass from belts 150 downwardly over the rear end 172 of guide plate 170 and into cup C5 of the distributor.

The second pin of a set of ten pins, in engaging switch A, opens switch A but does not stop motor M3, since it is still energized by the separate circuit described above. In passing switch B, however, this second pin, in closing contacts 282, establishes the circuit to index relay PR2 since relay LR6 is now latched. The operation of the index relay PR2 effects actuation of solenoid S2, whereby the clutch 126 effects one cycle, thereby indexing the distributor frame 102 the required distance to locate cup C9 in pin receiving position.

Since actuator b of switch B, as shown in Fig. 3, is located at a considerable distance from the pin loading station, the cup C9, moved as stated, has ample time to come to rest in pin receiving position before the pin passing actuator b of switch B can reach that cup. As the pin is carried by the belts 150 of transport K towards distributor D, it will engage actuator c of switch C, closing contacts 286 and again energizing the latch coil of latch relay LR6. Since this relay is already latched, no change is effected in that circuit.

The distributor frame 102, in moving cup C9 to the loading position as a result of the single actuation of clutch 126, causes cam element 222 on cam 140 to move out of engagement with switch DC causing its contacts 259 to assume their normal closed position. This causes the shunting of the relay TR2 normally open contacts 262 in the relay LR3 coil circuit and provides a source of power to the LR3 coil until switch DB is actuated as a result of the receipt of a full load by the distributor. This new circuit now supplying power to the LR3 coil circuit consists of DB cam switch normally closed contacts 256, DC cam switch normally closed contacts 259 and LR6 relay normally open contacts

253, now closed due to the latched condition of LR6 relay.

It should here be noted that, as shown in Fig. 4, the cam lobes 202-216 are equally spaced from each other reading in the above order. The center to center distance of this spacing in the present instance is 40°. The distance directly between cam lobe 202 and cam lobe 216 is, however, 80°. The roller 217 on the actuator 218 is disposed midway between the cam lobes 202 and 216, thereby being 40° from either lobe at this time. The arrangement of the cam lobes and the switch DA is such that each 40° movement of cam lobes 202-216 in the direction of the arrow, Figs. 3 and 4, is equivalent to two index steps of distributor frame 102 to be made following two actuations of the one revolution clutch 126.

Figs. 3 and 4 illustrate the position of the parts 20 after a first pin P of a new set has been carried by transport K and delivered into cup C5. The travel of that pin through the transport mechanism and its actuation of the various switches A, B and C, causes no indexing of the distributor. 25 However, passage of the second pin through the transport mechanism, as described above, causes a single indexing of the distributor to place cup C9 in position to receive that second pin. In this action cam 140 will travel 20° through the one actuation of the clutch 126 carrying point 203 (shown in Fig. 4) to a position opposite the roller 217 of the contactor 218 of switch DA.

Upon the passage of the third pin of a new set of pins through the transport mechanism K, its actuation of switch B will now cause the distributor frame to rotate 20° by actuation of solenoid S2 and closing of the clutch 126. Before this 20° movement is completed, the cam switch DA is closed, effecting a second operation 40 of solenoid S2 and clutch 126, since point 202 moves into engagement with roller 217 of actuator 218 of switch DA, thereby completing the movement for the required 40° to position cup C10 at the loading station opposite the transport mechanism to receive the third pin, which 45 just previously had actuated switch B.

The distributor frame 102 action, as just described, occurs while the third pin is travelling along the belts 150 and is completed before that pin reaches and engages actuator c of switch C. 50 This action is assisted by the relative speeds of the belts 150 and the distributor frame 102. The mechanism is so designed that the time required for the distributor to make one indexing movement is less than the time required for a pin to be moved by belts 150 from switch B to switch C. The distributor frame 102 indexing, as stated, is faster than the belt travel, so that its movement step by step is always sufficient to insure that 55 the desired empty cup comes to rest at the loading station before the pin can enter it.

Similarly, the delivery of the fourth pin into cup C6 and successive pins into cups C3, C1, C2, C4, C7 and C8, respectively, is effected, as described above, by sequential double indexing of the distributor frame by reason of the spacing of the remaining lobes 204-216 on cam 140.

The indexing operation which brings cup C8 into pin receiving position relative to transport 70 K to receive the tenth and last pin of a set, causes switch DB to be actuated by cam projection 220, as stated. When the normally open contacts 257 of this switch are closed, relay LR6 unlatching coil is energized to unlatch that relay and open contacts 250 and 253 thereof and

close contacts 252 thereof. The contacts are thus shown in the circuit diagram, Fig. 9, and relay LR6 is shown in open position as a consequence.

The foregoing operations open the circuit including the holding circuit for the coil of relay LR3, shunting the normally closed contacts on switch A so that any succeeding pin (which would be the first pin of a new set) being delivered by the pin elevator mechanism and coming into contact with switch A, will open normally closed contacts 273 of switch A and thereby remove power from the coil of relay LR3 and cause its contacts 289 to open and stop motor M3. This stops the operation of the pin elevating mechanism and the transport belts 150. That pin will thus stop adjacent switch A and remain there until after the distributor is unloaded. In this manner, such a pin cannot be carried by the transport mechanism K and dumped upon the fully loaded distributor. Motor M3 may be equipped with a suitable brake of conventional design that quickly stops the drive to the elevator and the transfer belts whenever the power to the motor is interrupted.

The diagram of Fig. 9 illustrates a latching relay LR4, the unlatching coil of which is operable by the table cam TH which operates the switch shown associated therewith when the table T goes through a spotting operation for setting pins on the alley. Cam TH as well as a cam TG are mounted on the cam shaft 290, see Fig. 9. Such a cam shaft may be suitably driven by the table cam shaft 241 to insure cyclic operation thereof in timed relation to the distributor drive means to enable all operations of the distributor, pin delivering devices and the controls to occur at the desired relative times in a bowling sequence. Thus in order to maintain corresponding rotary motions between shafts 241 and 290 and to enable the operation of distributor D, the pin delivery cups C, and the associated controls in the desired sequence, shaft 241 is provided with a sprocket 340 on which runs a chain 341 engaging and driving sprocket 342 fixed to control cam shaft 290 which supports cams TG and TH (see Figs. 3 and 9).

Since such cam shaft drive means are fully disclosed in the pending Fluke and Flint application, detailed description in the present disclosure is deemed unnecessary.

When relay LR4 is unlatched, as shown, contacts 254 thereof are closed. Cam TG on shaft 290 is operable to close the contacts 292 of the switch associated therewith when the table is in the correct position to receive pins. Relay TR3 is the control relay for the machine which is de-energized on a first ball and is energized on a second ball. The construction and operation of this control means are fully shown and described in the above referred to Flint and Fluke application, and further description herein is deemed unnecessary. The relay is also energized by the detection of a strike or of a foul on a first ball of a frame, and affects the operation of the machine to effect a proper discharge of pins from the distributor cups into funnels F of spotter table T. When the distributor D has received a full load of ten pins and conditions for unloading these pins into the table have been met, such for example, as all of the table funnels F being empty, the table T in correct position to receive pins from the distributor D, and its timing cycle being in order, a circuit is set up consisting of distributor cam operated switch DB contacts 257 which are closed and contacts

252 of relay LR6 which are closed since relay LR6 is energized. TG cam holds its switch contacts 292 closed, relay TR3 contacts 264 are closed, and relay LR4 contacts 254 are closed, causing index relay PR2 to be operated and close its contacts 294. This causes distributor indexing solenoid S2 to trip the clutch 126 for one revolution. When the distributor frame 102 has moved approximately 10° of the 20° final unloading index, switch DB operates opening contacts 257, and closing contacts 256 thereby interrupting the foregoing circuit through the coil of relay PR2 so that solenoid S2 is de-energized. This action stops the distributor after its final 20° of rotation has been completed.

When the distributor is in the loaded position, with the spider 114 with its pin supports 115 still positioned to support pins in the cups, the finger 192 on the spider engages stop 194, previously described.

As the distributor then moves through the last 20° index for unloading the pins, the spider is retained in contact with stop 194 so that it fails to follow the distributor, thereby clearing the bottoms of the cups to permit the pins to fall therethrough.

Near the completion of this last index, switch DC is actuated by cam projection 222 to close the contacts 253 of that switch and thereby energize relay PR3 closing contacts 296. Relay PR3 is preferably a delayed action relay which is adjustable to close contacts 296, say one second after energization of its coil. This insures ample time to be provided for all pins to be located in the table funnels F before spider 114 is released for return to its operative position by spring 185 relative to the cups on distributor frame 102. Obviously a larger or a shorter period of time could be provided, if desired.

Closing of this relay operates solenoid S3, thereby raising lever 196 so as to carry stop roller 194 out of engagement with spider finger 192, whereupon the spider, under the action of spring 185, advances to carry the pin supports 115 thereof into pin supporting position beneath the distributor cups in which position the spider is again latched to the distributor by the latch mechanism associated with cup C5, as previously described.

In assuming this position, the spider carries cam plate 232 on post 230 into position to engage and close spider switch 234, thus energizing relay TR2 and closing contacts 260 and 262 thereof.

In this way power is applied through the now closed contacts 256 of cam switch DB, contacts 253 of switch DC and contacts 260 of relay TR2 to the latching coil of relay LR4 to latch this relay.

When contacts 262 of relay TR2 close, power is also supplied to the relay LR3 of motor M3 through switch contacts 256, contacts 253 of switch DC and contacts 262 of relay TR2. This starts the motor M3 for the elevator and transport if it had been stopped as a result of a pin reaching switch A after the distributor is loaded.

The foregoing operations constitute one loading and unloading cycle of the distributor which is now in position to receive a new set of pins.

From the foregoing description of the present invention it will be observed that latch-type relays are used in connection with the control of the functions of the bowling pin spotting machine. It is believed obvious that, as a result, a power shut-off for example, while stopping the

machine, will not change or throw out of phase its cyclic operation, since the latch relays will retain all parts locked up until power is restored.

The machine will then proceed where it left off and continue the action of any incompletely cycles or performance in proper phase or sequence.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. A bowling pin spotting machine having a movable distributor frame provided with a plurality of substantially triangularly arranged pin cups for receiving pins and positioning said pins in substantially upright position therein, pin elevating mechanism from which pins are delivered in succession, means for transporting said delivered pins one after another to selected cups on said distributor frame, means for driving said pin elevator, said pin transport and said distributor, means operable by a pin moving on said transport for intermittently actuating said distributor drive means to move said distributor pin cups successively into position to receive pins from said transport, and other means associated with said pin transport and operable by a pin transported thereby for stopping said pin elevating mechanism and said pin transport drive means when each of said cups in said frame has received a pin.

2. A bowling pin spotting machine having an intermittently movable distributor frame, a plurality of pin receiving cups mounted on said frame, an electrically controlled device for indexing said distributor to position said cups to receive pins therein one after another, an electrical circuit having means for actuating said device, a pin transport mechanism including a pair of spaced V-belts to carry pins endwise therewith to said distributor, pin elevating mechanism for delivering pins to said V-belts of said transport mechanism, means for driving said V-belts and said pin elevating mechanism, a switch in said circuit operable by pins carried by said V-belts to actuate said device to effect sequential indexing of said distributor until each of said cups contains a pin, and a second switch in said circuit also engageable by pins moving along said transport, and means operative in response to the engagement therewith of the first pin of the next set of pins to be fed to said distributor to stop said driving means and thereby prevent additional pins from reaching said distributor.

3. A bowling pin spotting machine having a movable distributor frame provided with pin cups for receiving pins, pin elevating mechanism from which pins are delivered in succession, means for transporting said delivered pins one after another to said distributor, means for driving said distributor frame to move said pin cups thereon successively into a position to receive pins from said pin transport, means associated with said transport mechanism and operable by pins transported thereby for intermittently actuating said distributor drive means, means operated by the first pin of a new set of pins advanced by said transporting means for preventing movement of said distributor, means for rendering said preventing means inoperative in response

to the delivery of the first pin of a set of pins into a selected cup on said frame, and other means incapacitating said distributor frame drive means when all of said cups on said frame are filled.

5. 4. In a bowling pin spotting machine for use with a bowling alley having a pit at one end thereof, a pin spotter, said spotter being provided with a plurality of pin spotting units, and means for moving said spotter to and from the 10 pin supporting deck of a bowling alley for spotting a set of bowling pins in playing arrangement thereon, a distributor mounted above said spotter including a movable series of pin supporting cups, a conveyor for delivering pins one by one to said 15 cups, an elevator for delivering pins from said pit to said conveyor, an indexing device for said movable series of cups, control means spaced along said conveyor and actuated by pins moved by said conveyor to said cups for intermittently 20 actuating said indexing device to move said cups to present empty cups seriatim for delivery of pins thereto, said control means including a device actuated by the first pin of a set advanced by said conveyor for preventing movement of said 25 series of cups, and means for rendering said device inoperative in response to the delivery of the first pin of a set into a selected cup on said frame.

5. In a bowling pin spotting machine having a pin spotting table and means for raising and 30 lowering said table to spot bowling pins in playing arrangement on the bowling deck of an alley, a movable distributor mounted above the path of travel of said table, said distributor being provided with spaced pin supports for receiving and 35 supporting pins to be delivered to said spotter table, pin elevating mechanism, a pin transporting conveyor to receive pins from said pin elevating mechanism and convey pins one after another to a point of discharge into the said 40 supports, means for moving said distributor to locate said pin supports successively at said point of discharge to receive pins from said pin transport conveyor, a plurality of pin actuated control means associated with said transport conveyor and operable by pins transported by said conveyor for intermittently actuating said distributor moving means, and means mounting 45 said pin actuated control means at spaced points along said transporting conveyor for engagement by pins advanced thereby and at a distance 50 from said point of discharge such that the intermittent motion of said distributor occurs and stops prior to the arrival of the pin which actuated said pin actuated control means at said 55 point of discharge.

6. In a bowling pin spotting machine for use with a bowling alley having a pit at one end thereof, a device for spotting and respotting pins on the playing bed of a bowling alley, said device 60 having a plurality of pin spotting units and a plurality of respotting units mounted thereon, and means for moving said device to and from the pin supporting deck of a bowling alley for spotting a set of bowling pins in playing arrangement thereon, a pin assembling and distributing mechanism, said mechanism including a movable member provided with a plurality of spaced pin cups, a second movable member provided with a plurality of pin supporting surfaces mounted 65 beneath said cups, and constructed and arranged to coat therewith for holding pins in each of said cups, a device for maintaining said members in pin receiving and supporting relationship, a conveyor for delivering a succession of pins 70 removed from said pit to a point of discharge into 75

said cups on said first-named member, means for locating a selected cup at said point of discharge to receive the first pin of a set of pins delivered by said conveyor, a device on said first member for maintaining said members with said selected cup positioned to receive said first-named pin until a pin is located in said cup, means operative in response to the movement of each succeeding pin along said conveyor for intermittently moving said members to locate empty cups in succession at said point of discharge after said first pin has been delivered into said selected cup, means for terminating the movement of said second-named member when all of said cups contain a pin, means for rendering said device inoperative in response to the filling of all of said cups, and means for effecting relative movement between said first-named member and said second-named member to effect the discharge of bowling pins therefrom into said spotting units.

7. The invention set forth in claim 6, wherein said means for effecting relative movement between said first-named member and said second-named member includes an electrically released stop device, and a solenoid for moving said stop device out of the path of travel of said second-named member to allow the movement of said second-named member relative to said first-named member, means for restoring said members to pin supporting relationship, and means for delaying the return of said members to operative pin supporting relationship after the discharge of pins from said cups until all pins have been delivered into said spotting units.

8. A distributor mechanism for a bowling pin spotting machine comprising an elongated infeed conveyor, means for driving said conveyor, a movable supporting member, a plurality of bowling pin supports mounted on said member, means for driving said member at a greater rate of speed than the speed of said infeed conveyor, a pin elevating device for delivering pins to said infeed conveyor, means for driving said device at a rate of speed slower than the speed of said infeed conveyor, and control mechanism including devices actuated by pins advanced to said supports for controlling the movement of said movable supporting member and for stopping said means for driving said infeed conveyor and said means for driving said elevating device when a bowling pin has been delivered to each of said pin supports, and means for effecting the gravity discharge of said pins from said supports.

9. The invention defined in claim 8, wherein said control mechanism includes an electric circuit, and said devices include pin actuated switches in said circuit and spaced along said conveyor and adapted to be engaged by each pin fed by said conveyor.

10. The invention defined in claim 9, wherein said circuit of said control mechanism includes a sub-circuit for controlling the movement of said movable member to effect the delivery of the first pin to be delivered by said infeed conveyor into a selected support on said movable member, a second sub-circuit for controlling and effecting a step by step movement of said movable member in effecting the delivery of a succession of pins to fill all supports on said member, and a third sub-circuit for preventing the movement of said movable member when each of said supports contains a bowling pin, said sub-circuits including said pin actuated switches.

11. The invention defined in claim 10, wherein said circuit of said control mechanism includes

a latch relay for holding in the third sub-circuit after a bowling pin has been delivered by said conveyor to each of said supports on said movable member, and means for automatically unlatching said latch relay on discharge of said pins from said supports to prepare said distributor for the delivery of a new set of pins to said supports.

12. The invention set forth in claim 10 wherein said control mechanism includes a latch relay in said second-named sub-circuit, means operative after the first pin of a new set of pins has been delivered into said selected support for energizing said latch relay to maintain said circuit during all movements of said movable member in locating empty supports in position to receive a pin from said infeed conveyor, means for de-energizing said latch relay to break said circuit when all supports on said member contain a pin, a second latch relay in said circuit, means for energizing said second latch-relay when all of said supports contain pins, and means for de-energizing said second latch-relay upon discharge of all pins from said supports to prepare said distributor for the delivery of a set of pins to said empty supports.

13. A bowling pin spotting machine having an intermittently movable distributor provided with a plurality of substantially triangularly arranged pin receiving and supporting cups, an electrically controlled device for indexing said distributor to receive pins therein one after another, an electrical circuit having therein means for actuating said device, a pin transport mechanism including a conveyor to carry pins endwise therealong to said distributor, means for driving said conveyor, a switch in said circuit operable by pins carried by said conveyor to actuate said first-named means to cause said device to effect an intermittent indexing of said distributor until a predetermined number of pins has been assembled therein, and a second switch in said circuit also engageable by pins passing on said conveyor, and means operative by said second switch in response to the first pin of the next set of pins to be fed to said distributor by said conveyor for stopping said driving means and thereby preventing additional pins from reaching said distributor.

14. A bowling pin spotting machine having a movable distributor frame provided with pin cups for receiving pins, pin elevating mechanism from which pins are delivered in succession, means for transporting said delivered pins one after another to said distributor frame, normally inoperative means responsive to the movement of successive pins towards said cups for driving said distributor frame to move said pin cups thereon successively into a position to receive pins from said pin transporting means, and means responsive to the delivery of the first pin of a new set of pins into a selected pin cup for conditioning said distributor frame driving means for operation in response to the movement of subsequent successive pins of said set of pins towards said pin cups.
